(57) **CLAIM**

The ornamental design for a baby sleeping bag, as shown and described.

DESCRIPTION

FIG. 1 is a perspective view of a baby sleeping bag design showing my new design.

FIG. 2 is a front view of a baby sleeping bag.

FIG. 3 is a rear view of a baby sleeping bag.

FIG. 4 is a left side view of a baby sleeping bag.

FIG. 5 is a right side view of a baby sleeping bag.

FIG. 6 is a top view of a baby sleeping bag.

FIG. 7 is a bottom view of a baby sleeping bag.

FIG. 8 is a perspective view thereof, showing the baby sleeping bag in a state of separation; and,

FIG. 9 is a perspective view thereof, showing the baby sleeping bag in an open state of use.

The broken lines in the drawings depict portions of the baby sleeping bag that form no part of the claimed design.

It is certified that error appears in the above-identified patent and that said Letters Patent is hereby corrected as shown below:

On the Title Page

Delete the title page and substitute therefore with the attached title page consisting of the corrected illustrative figure(s).

In the Drawings

Please replace FIGS. 1-7 with FIGS. 1-7 as shown on the attached pages.

Signed and Sealed this
Twenty-second Day of April, 2025

Coke Morgan Stewart
Acting Director of the United States Patent and Trademark Office
